UNITED STATES PATENT OFFICE

106,071

DESIGN FOR A CONFECTION CONE

Frank B. Stuart, Knoxville, Tenn.

Application July 26, 1937, Serial No. 70,670

Term of patent 14 years

To all whom it may concern:

Be it known that I, Frank B. Stuart, a citizen of the United States, residing at Knoxville, in the county of Knox, and State of Tennessee, have invented a new, original, and ornamental Design for a Confection Cone, of which the following is a specification, reference being had to the accompanying drawing, forming part thereof.

I claim:

The ornamental design for a confection cone, as shown.

FRANK B. STUART.
